UNITED STATES PATENT OFFICE.

ALFRED C. TYTLER, OF SAN FRANCISCO, AND JOHN W. SOMERVILLE, OF SANTA CRUZ,
CALIFORNIA.

FAUCET.

Application filed August 13, 1923. Serial No. 657,171.

To all whom it may concern:

Be it known that we, ALFRED C. TYTLER and JOHN W. SOMERVILLE, citizens of the United States, residing at San Francisco, 5 in the county of San Francisco, and Santa Cruz, in the county of Santa Cruz, respectively, and State of California, have invented new and useful Improvements in Faucets, of which the following is a specification.

10 The object of our said invention is the provision of a faucet embodying a simple, efficient and easily controlled equipment whereby the faucet may be cut off from a source of fluid supply so as to permit of 15 the faucet or valve being repacked or otherwise repaired without affecting the connection between other faucets or valves and the said source of supply.

To the attainment of the foregoing, the 20 invention consists in the improvement as hereinafter described and definitely claimed.

In the accompanying drawings, forming part of this specification:—

Figure 1 is a side elevation of a faucet 25 or valve embodying our invention.

Figure 2 is a sectional view of the same.

Figure 3 is an enlarged detail section taken in the plane indicated by the line 3—3 of Figure 2.

30 Similar numerals of reference designate corresponding parts in all of the views of the drawings.

The body 1 of our novel faucet or valve is in general of the ordinary well known form 35 and construction, being provided with a bonnet 2 and combined with an ordinary stem 3 on which is a handle 4 and a head 5, the latter carrying renewable packing 6, attached to the stem in any appropriate manner.

40 The body 1 is provided with the usual interior apertured partition 7, and combined with the said body 1 and the said partition 7 are the elements comprised in our novel equipment. The said equipment or improve- 45

ment comprises an outer apertured barrel 8, an inner apertured barrel 9 arranged and adapted to be turned about its axis in the outer barrel 8, a collar 10, a finger piece 11 complementary to the inner barrel 9 for the 50

convenient turning of the latter and arranged with the collar 10 exteriorly of the body 1, and a washer 12 interposed between the collar 10 and the lower end of the barrel construction to assure said construction being 55

the barrels 8 and 9 are by preference, of corresponding size to the outlet of the body 1 in order to assure the supply of a full head of water when the inner barrel 9 is placed therefor.

Manifestly when the apertures in the barrels 8 and 9 are in registration a clear passage for water is afforded through the barrels and into the outer portion of the body 1 provided, of course, that the valve head is 60 spaced from its seat. When, however, the inner barrel 9 is turned to close the apertures in the barrels, the supply of fluid to the valve seat will be precluded. From this it follows that in the last stated position of 70 the inner barrel 9 the bonnet 2 and the stem 3 with the appurtenances of the latter may be conveniently removed from the body 1 for the renewal of packing on the head 5 or for any other purpose. It also follows 75 that the operation indicated may be carried out without the necessity of cutting off the source of fluid supply from valves or faucets other than the one herein illustrated and described.

80 In practice when it is desired to renew the packing 6 it is simply necessary for the operator to properly turn the barrel 9 through the medium of the finger piece 11, and when it is desired to restore the faucet 85 to operation it will be necessary for the operator through the medium of the finger piece 11 to position the barrel 9 with its aperture in registration with the aperture of the outer barrel 9. It will further be noted 90 that the outer barrel comprised in our improvement constitutes an adequate valve seat.

Notwithstanding the practical merit of our improvement it will be apparent that the improvement adds but little to the cost of 95 an ordinary faucet or valve.

We have entered into a detailed description of the construction and relative arrangement of the parts embraced in the present and referred embodiment of our invention in order to impart a full, clear and exact understanding of the said embodiment. We do not desire, however, to be understood as confining ourselves to the specific construction and relative arrangement of parts inasmuch as in the future practice of the invention various changes and modifications may be made such as fall within the scope of our invention as defined in our appended claim.

Having described our invention, what we claim and desire to secure by Letters-Patent, is:—

5 In a faucet or valve, the combination of a body, a stem working in the body and equipped with a head, inner and outer apertures, and control of the passage of fluid past the same, one of the barrels constituting a seat and 10 the other and inner barrel having means

exterior of the body for the turning thereof, a flanged collar on the exterior portion

of the inner barrel and threaded on the outer

barrel, and packing confined in said collar

and against the outer barrel.

In testimony whereof we affix our signatures.

ALFRED C. TYTLER.
JOHN W. SOMERVILLE.
